UNITED STATES PATENT OFFICE

FRED RICKS AND ALFRED EDWARD RICHARDS, OF LEICESTER, ENGLAND, ASSIGNEES
TO UNITED SHOE MACHINERY CORPORATION, OF PATERSON, NEW JERSEY, A COR-
PORATION OF NEW JERSEY

HEEL-SEAT-FITTING MACHINE

Application filed January 5, 1926, Serial No. 79,457, and in Great Britain January 13, 1925.

This invention relates to machines for operating upon shoe parts and is illustrated herein as embodied in a machine arranged to perform the heel-seat fitting operation upon soles prior to their attachment to shoes.

In the manufacture of shoes to which wood and some other kinds of heels are to be attached it is usual to fit the heel-seat portions of the soles of the shoes for the reception of the concave or cupped attaching surfaces with which such heels are provided by trimming surplus stock from the peripheral portions of the heel-seats of the soles. This is preferably done by a cut inclined relatively to the surface of the heel-seat so that the periphery of the heel-seat is beveled in conformity to the concave attaching face of the heel, the material thus removed having an approximately horseshoe-shaped form. The stock at the forward extremities of the bevel is cut to produce a pair of heel-breast engaging shoulders or other appropriate heel-breast engaging formation.

It is an object of the present invention to provide a simple, inexpensive and reliable machine for performing this heel-seat fitting operation. With this object in view the illustrated machine is provided with means for deforming the heel-seat of a sole so that a knife moved longitudinally from the rear may cut the peripheral portion from a heel-seat, beveling the edge of the heel-seat and leaving the chip thus formed attached to the sole approximately at the heel-breast line. The machine is also provided with means by which the work is then repositioned so that, by further movement of the knife, the chip may be severed from the sole.

A feature of the invention comprises work-positioning means arranged to be straddled by the work so that one portion of the work may be operated upon while another portion is guarded from the operating means. In accordance with this feature, the illustrated heel-seat fitting machine is provided with a bar arranged to receive the work with the heel-seat portion of the sole to be operated upon on one side of the bar and a chip trimmed from the sole peripherally of the heel-seat but attached to the sole approxi-

mately at the heel-breast line on the other side of the bar, in combination with a knife operable to sever the chip from the sole while the heel-seat portion of the sole is thus guarded by the bar. In accordance with a further feature of the invention, the formation of this bar and its relation to the path of movement of the knife are such that the severing of the chip results in the formation of a pair of tabs having beveled ends adapted to overlie the overhanging breast of a Louis heel, forming an abutment against which the heel may be positioned when it is being located for attachment to the shoe and reinforcing the attachment of the heel to the shoe. It should be noted, moreover, that the formation of the bevel cut peripherally of the heel-seat prior to the severing of the chip causes the inner edges of these tabs also to be beveled so that when the tabs are pressed into engagement with the breast of a Louis heel, they merge into its surface in such a way that after the breast of the heel is covered with the usual flap, they in no way injure its appearance. If the soles to be operated upon are for shoes having heels of such a nature that tabs of this formation are not desired, for example if the shoes are to have Cuban heels, by an appropriate change in the formation of the bar straddled by the heel-seat portion of the sole and the chip, the chip may be severed exactly at the heel-breast line at right angles to the surface of the sole, or, within reasonable limits, at any other desired position and angle.

While the illustrated machine is adapted particularly to perform the heel-seat fitting operation upon soles prior to their attachment to shoes, it should be noted that the invention is not limited to a machine for performing the operation upon soles prior to their attachment to shoes, and, indeed, in various of its aspects it is applicable to machines for performing other operations.

With the above and other objects and features in view, the invention will now be described with reference to the accompanying drawings and pointed out in the claims.

In the drawings,

Fig. 1 is a plan view of a preferred machine embodying the present invention;

Fig. 2 is a side elevation of the same machine partly in section;

Fig. 3 is a detail view, illustrating in longitudinal section, the cutting of the horseshoe-shaped, peripheral chip whereby the edge of the heel-seat of the sole is beveled;

Fig. 4 is a longitudinal section illustrating the severing from the sole of the horseshoe-shaped chip;

Fig. 5 is a side elevation of the rear portion of a sole after it has been operated upon as illustrated in Figs. 3 and 4; and

Fig. 6 is a plan view of the sole of Fig. 5 viewed from its attaching surface.

The illustrated machine is provided with a frame 10 having in its upper horizontal face a guideway 12 extending from front to rear of the machine. Mounted in the guideway 12 is a slide 14 having pivotally connected to it one end of a link 16 which is pivotally connected at its other end to a hand lever 18 pivoted at 20 on the frame 10 by which lever 20 the slide 14 may be moved forwardly and rearwardly in the guideway 12. The slide 14 has fixed to it a splitting or trimming knife 22 having a cutting edge extending across the machine. The knife edge as it travels forward and backward moves over and in light contact with the upper face of a plate 24 fixed to the frame 10 below the guideway 12. The plate 24 has formed in it a suitably shaped opening 26 (Fig. 1) through 25 which the centre portion of the heel end of the sole is thrust by a die 28 which has a convex upper face and which is carried on the upper end of a plunger 30 slidably mounted in the frame and moved upwardly to thrust 30 the central part of the heel portion through the opening 26 in the plate 24 by a treadle-operated lever 32 pivoted at 34 on the frame. The plunger 30 is returned by its own weight and its upward movement is limited by an adjustable screw 36 mounted in the frame and 35 in position to be engaged by the lever 32. The plate 24 is beveled on its under side to provide a thin margin round the edge of the opening 26, as shown at 38, and the beveled 40 face at the sides of the opening has formed on it serrations or teeth 40 to hold the sole against lengthwise movement during the cutting operation. The plate 24 may be adjusted forwardly or rearwardly to bring the opening 45 26 into proper relation to the die 28, screw and slot connections 42 being provided for this purpose. Forward movement of the splitting knife 22 is limited by an adjustable stop screw 44 fixed in the slide 14 and engaging a stop in the form of a projection 46 on the plunger 30 when the plunger is in its raised position. Adjustably fixed to the under side of the plate 24 behind the opening 26 is an end gage 48 arranged to position

the heel end of the sole when it is presented beneath the plate 24 and over the die 28.

In the operation of forming the horseshoe-shaped margin a sole 50 (Fig. 3) which may have previously had formed on it a flap 52 (which in the finished shoe extends over the breast face of a Louis heel) is positioned in the machine over the die 28 with its heel and against the gage 48. The die 28 is then raised, as far as is permitted by the adjustable stop screw 36, to engage that face of the sole on which the breast flap 52 is formed and to bulge the opposite face of the sole through the opening 26 in the plate 24. The stop screw 36 is so adjusted that when the splitting knife 22 is moved forward by means of the hand lever 18 the knife 22 will enter the sole face near the heel end and will split, progressively towards the toe end, that portion of the sole which is bulged through the plate, cutting right through to but not into the breast flap 52. The knife 22 is then moved back out of the way and the sole removed from the machine. The edges of the portions thus parted are, owing to the bulging, beveled as shown at 54. The distance along the sole to which the split is carried is determined by the adjustable stop screw 44 on the frame which engages the projection 46. This splitting action forms on the sole a flap 56 (Figs. 3 to 6), connected at its inner end to the sole, which has formed on it the convex or bevel-margin surface 54 to receive the concave heel-seat surface of the heel and this flap is surrounded by a horseshoe-shaped chip or trimming of material 58 which is still connected at its opposite ends (at each side of the flap 56 at the termination of the cut) to the sole approximately at the heel-breast line. This strip 58 is later severed from the sole by the knife 22. For this purpose strip 58 is inserted between a bar 60 and the knife 22, in the position shown in Fig. 4, with the heel-breast flap 52 turned up out of the path of the knife 22 and the heel-seat flap 56 extending down in front of the machine and in front of a gage bar 62 which functions to guard the flap 56 during the chip severing operation and which is adjustably secured to the frame of the machine by screw and slot connections 64. Gage bar 62 extends into the angle between the portion 58 to be cut off and the convex heel-seat flap portion 56, the work thus straddling bars 60 and 62. The portion 58 to be cut off is thrust down as far as is permitted by the gage bar 62 so that the position of this gage determines the position along the sole at which the cuts are made. Gage bar 62 also guards the heel seat portion of the sole from injury by the knife 22 as the portion 58 is cut off. The angle of the cuts, shown at 63, is determined by the angle of the upper face of the bar 60 against which the horseshoe-shaped trimming is pressed by the knife 22, bar 60 thus co-operating with

knife 22 to cut with a shearing action and the two thus forming a pair of shear members. The upper surface of bar 60 is serrated to prevent movement of the trimming by the knife 22. The cuts through the horseshoe ends extend forwardly of the sole from the tread face, that is the face adjacent to the breast flap, toward the attaching face. The die 28 is at this time in its lowered position and the stop 46 is therefore out of the path of the stop-screw 44 so that the slide or carrier 14 can be moved further forward, beyond the position determined by the stop 46 and screw 44, to cause the knife 22 to make the severing cuts. The extent of this latter movement is limited by the engagement of a portion of the slide 14 with the frame or by any other suitable arrangement.

When the material is removed in the manner just described, short beveled projections or tabs 66 remain extending towards the heel end of the sole alongside the convex heel-seat flap 56 at opposite sides of the sole. These tabs 66 are well adapted to buttress and position a Louis heel longitudinally, in part by the junction of the heel-breast and heel-seat of the heel seating itself against the junctions of the projections and the heel-seat of the sole where the first knife cut terminates and in part by the contact of the projections themselves against the heel-breast, it being understood that in the finished shoe the projections extend up the breast face of the heel and lie on it beneath the breast flap. Since the tabs 66 are beveled transversely, they may, if necessary, be moved in or out a little to cause their outer edges to line up with the breast corners of the heel. Also their beveled ends cause them to merge unnoticed into the breast surface of the heel.

Having described the invention, what we claim as new and desire to secure by Letters Patent of the United States is:

1. A heel-seat fitting machine having work-positioning means at two different stations in the machine, and a cutter arranged to trim material from the periphery of the heel-seat portion of a sole positioned at one of said stations and to sever the chip thus formed from the heel-seat portion of a sole positioned at the other station.

2. A heel-seat fitting machine having a rectilinearly movable trimming knife, and work-positioning means at two different stations in the path of movement of the knife arranged to dispose the work relatively to the knife so that the knife trims the material from the periphery of the heel-seat portion of a sole positioned at one of said stations and severs the chip thus formed from the heel-seat portion of a sole positioned at the other station.

3. A heel-seat fitting machine having means for trimming material from the

periphery of the heel-seat portion of a sole arranged to leave a chip attached to the sole adjacent to the heel-breast line of the sole, other means for holding the chip spaced from the heel-seat portion of the sole, and means for severing the chip from the sole while thus spaced from the heel-seat.

4. A heel-seat fitting machine having a knife to trim material from the periphery of the heel-seat portion of a sole arranged to leave a chip attached to the sole adjacent to the heel-breast line of the sole, and a bar arranged to be straddled by the sole and the chip thereby holding the chip spaced from the heel-seat of the sole, whereby the chip may be severed from the sole by subsequent movement of the knife.

5. A heel-seat fitting machine having a knife, and means for operating the knife first to trim a chip from the periphery of the heel-seat portion of a sole and thereafter to sever the chip from the entire sole by a cut adjacent to the heel breast line.

6. A heel-seat fitting machine having a plate provided with an approximately horseshoe-shaped opening, a die arranged to force the central portion of the heel-seat of a sole through said opening, a stop movable with the die, a knife, means for moving the knife to trim the peripheral portion from the heel-seat of a sole held by the die and plate, and a stop moving with the knife arranged by engagement with the first-named stop to limit the movement of the knife relatively to the sole.

7. A heel-seat fitting machine having a plate provided with an approximately horseshoe-shaped opening, a gage arranged to locate a sole relatively to said opening, a die arranged to force the central portion of the heel-seat of a sole through said opening, a stop movable with the die, a knife, means for moving the knife lengthwise of the sole to trim the peripheral portion from the heel-seat of a sole thus held by the die and plate, and a stop moving with the knife arranged by engagement with the first-named stop to limit the movement of the knife lengthwise of the sole, the first-named stop being arranged to be withdrawn from the path of movement of the knife after the knife has completed its trimming movement to permit further movement of the knife.

8. A heel-seat fitting machine having a plate formed with an approximately horseshoe-shaped opening, a die arranged by relative movement of the die and the plate to force the central portion of the heel-seat of a sole through said opening, thereby deforming the heel-seat portion of the sole so that the peripheral portion of the attaching face of the heel-seat is forced past the plane of the central portion of the tread surface of the heel-seat, a knife arranged for movement lengthwise of the sole to trim the peripheral

portion of the deformed heel-seat from the sole leaving the chip thus cut attached approximately at the heel-breast line, a stop arranged to limit the trimming movement of the knife, said stop being arranged to be withdrawn from the path of movement of the knife when by relative movement of the die and the plate the sole is released, means for positioning the sole with said chip in the path of movement of the knife whereby said chip may be severed by further movement of the knife permitted by the withdrawal of said stop, and a guard for protecting the heel-seat portion of the sole thus positioned from the knife as the latter severs the chip from the sole.

9. A heel-seat fitting machine having a plate formed with an approximately horse-shoe-shaped opening having a thin margin, a die arranged for movement toward said plate to force the central portion of the heel-seat of a sole through said opening, thereby deforming the heel-seat portion of the sole so that the peripheral portion of the attaching face of the heel-seat is forced past the plane of the central portion of the tread surface of the heel-seat, a knife arranged for movement lengthwise of the sole to trim the peripheral portion of the deformed heel-seat from the sole leaving the chip thus cut attached approximately at the heel-breast line, a stop movable with the die arranged to limit the trimming movement of the knife, said stop being withdrawn from the path of movement of the knife when the die is moved from the plate to inoperative position, means for positioning the sole with said chip in the path of movement of the knife whereby said chip may be severed by further movement of the knife permitted by the withdrawal of said stop, and a guard for protecting the heel-seat portion of the sole thus positioned from the knife as the latter severs the chip from the sole.

45 10. A heel-seat fitting machine having a knife, means for operating the knife first to trim material from the entire periphery of the heel-seat portion of a sole and thereafter to sever the trimming from the sole by a cut adjacent to the heel breast line, and means for guarding the heel-seat portion of the sole from injury during said severing operation.

11. A heel-seat fitting machine having work-positioning means, and a pair of shear members arranged to sever from a sole positioned by said means a previously formed chip separated from the sole peripherally of the heel-seat of the sole but attached to the sole at the forward end of the chip.

12. A heel-seat fitting machine having work-positioning means, a pair of shear members arranged to sever from a sole positioned by said means a previously partially detached chip, and means for guarding the sole from

injury during the operation of said shear members.

13. In a heel-seat fitting machine, means for holding apart the heel-seat portion of a sole and a peripheral chip trimmed therefrom but attached approximately at the heel-breast line, and means for severing said peripheral portion from the sole while thus held, said holding means being arranged also to guard the heel-seat portion of the sole from injury by said severing means.

14. A machine for operating upon shoe parts having a bar arranged to be straddled by portions of the work which are to be severed from each other, a knife arranged for movement transversely of the bar to sever the one portion from the other portion, and a guard arranged to protect one of the portions of the work during the severing operation.

15. A machine for operating upon shoe parts having a bar arranged to be straddled by portions of the work which are to be severed from each other, a guard to protect one of the portions, and a knife arranged for movement across said bar to sever the other portion.

16. In a heel-seat fitting machine means arranged to be received between the heel-seat portion of a sole and a peripheral chip trimmed therefrom but attached approximately at the heel-breast line, thereby to hold the heel-seat portion and the chip portion apart near the point of attachment, and means for shearing said peripheral chip from the sole while thus held.

17. A machine for operating upon shoe parts having a bar arranged to be straddled by portions of the work which are to be severed from each other, a guard also arranged to be straddled by portions of the work which are to be severed from each other to protect one of the portions, and a knife arranged for movement across said bar to sever the other portion.

18. A machine for operating upon shoe parts having a bar arranged to be straddled by portions of the work which are to be severed from each other, a guard also arranged to be straddled by portions of the work which are to be severed from each other and positioned nearer the point of severance than the said bar to protect one of the portions, and a knife arranged for movement across said bar to sever the other portion.

In testimony whereof we have signed our names to this specification.
